ITHAMAR W. STUART, JR., OF CHARLOTTESVILLE, INDIANA.

Letters Patent No. 62,978, dated March 19, 1867.

IMPROVED CAR-COUPING.

The Schedule referred to in these Letters Patent and making part of the same.

TO ALL WHOM IT MAY CONCERN:

Be it known that I, ITHAMAR W. STUART, Jr., of Charlottesville, in the county of Hancock, and State of Indiana, have invented a new and useful improvement in Car-Coupling; and I do hereby declare that the following is a full, clear, and exact description thereof, which will enable others skilled in the art to make and use the same, reference being had to the accompanying drawing, forming a part of this specification, in which—

The drawing represents my improved coupling, as attached to two adjacent cars, partly in section to show the construction.

My invention has for its object to furnish a convenient and reliable means for coupling and uncoupling cars without its being necessary to go between the cars for that purpose; and it consists in the form of the bumper-head, and in the combination therewith, and with the draught-bar and end of the car, of a coupling-link, chain, guard-latchet, and armed bar, as hereinafter more fully described.

A represents the ends of two adjacent cars to be coupled, B represents the draught-bars, and C the bumper-heads. The bumper-heads C are made in hook form or with upwardly projecting parts or arms. D is a bar or rod extending up vertically along the end of the car, as shown, so as to be reached and operated from the top of said car. To the lower end of the rod or bar D is attached an arm, d¹, which, when the rod or bar is pushed down, rests upon the upper side of the draught-bar B, as shown in the drawing. The arm d¹ is of such a length that its forward end enters and works in a slot formed in the inner side of the hook or arm of the bumper-head C. The lower end of the rod or bar D projects below the arm d¹, and enters a notch or mortise formed in the draught-bar B. d² is an arm attached to the bar D a little distance above the top of the bumper-head C, to the projecting end of which is pivoted a balance-latchet or guard, E, the lower end of which hangs in such a position that when the bar D is lowered it enters the groove in the inner side of the bumper-head C and prevents the removal of the link until the bar D has been raised. d³ is a stop pin, which enters a slot in the end of the car A, or in the standard against which the bar D is placed, and prevents the said bar from being moved too far in either direction. F is the coupling-link, which passes through a hole in the draught-bar B, as shown in the drawing. G is a chain, the ends of which are attached to the sides of the link F, and the middle part of which passes through a hole in the forward end of the arm d¹. The length of the chain may be regulated so as to raise the link F to any desired height.

In coupling the cars the bar D is raised, which raises the free end of the link F above the bumper-head C; then, as the cars come together, the bar D is lowered; the end of the link, striking against the latchet or guard E, by its weight pushes the said latchet out of the way and drops over the hook of the bumper-head C, the end of the latchet E at the same time entering the groove in the said bumper-head and guarding against the link's escaping therefrom. In uncoupling the cars all that is necessary is to raise the bar D; this lifts the link F above the end of the bumper-head, so that when the cars separate the said link may slide off.

Having thus described my invention, I claim as new, and desire to secure by Letters Patent—

1. The bumper-head C, when formed with an upwardly projecting part or hook grooved upon its inner side, substantially as herein shown and described, and for the purpose set forth.
2. The combination of the bar D, arms d¹ and d², balance-guard E, chain G, and link F, with each other, with the bumper C, draught-bar B, and end of the car A, substantially as herein shown and described, and for the purposes set forth.

ITHAMAR W. STUART, JR.
